(57) **CLAIM**

The ornamental design for stethoscope chestpiece, as shown and described.

DESCRIPTION

FIG. 1 is top, left side perspective view of my stethoscope chestpiece design;

FIG. 2 is a bottom, right side perspective thereof;

FIG. 3 is a left side elevation view thereof;

FIG. 4 is a right side elevation view thereof;

FIG. 5 is rear elevation view thereof;

FIG. 6 is front elevation view thereof;

FIG. 7 is a top plan view thereof; and,

FIG. 8 is a bottom plan view thereof.

The broken lines show portions of the stethoscope chestpiece that form no part of the claimed design.

1 Claim, 4 Drawing Sheets
